UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

DESIGN FOR A LANTERN.

Application filed September 12, 1921. Serial No. 500,215. Term of patent 14 years.

To all whom it may concern:

Be it known that I, JOSEPH W. GOSLING, a citizen of the United States, residing at Schenectady, in the county of Schenectady and State of New York, have invented a new, original, and ornamental Design for a Lantern, of which the following is a specification, reference being had to the accompanying drawing, forming a part thereof.

The drawing is a perspective view of my ornamental lantern, which is composed of the base or support member A, the intermediate or body portion comprising frame B

provided with openings in which are mounted panels C of light transmitting material, and the top or canopy portion comprising the frame D provided with openings in which are mounted panels E of light transmitting material and which terminates in a spike F.

I claim:

The ornamental design for a lantern as shown and described.

In witness whereof, I have hereunto set my hand this 10th day of September, 1921.

JOSEPH W. GOSLING.
